CLAIM

The ornamental design for an insert tray for insect trap, as shown and described.

DESCRIPTION

FIG. 1 is a top perspective view of an insert tray for insect trap showing our new design;

FIG. 2 is a top plan view thereof;

FIG. 3 is a front elevational view thereof;

FIG. 4 is an inverted back elevational view thereof;

FIG. 5 is a side elevational view, the opposite side being a mirror image thereof; and,

FIG. 6 is a bottom plan view of the design.
